UNITED STATES PATENT OFFICE

EDWARD A. SIPP, OF CHICAGO, ILLINOIS, ASSIGNOR TO THE PYLE-NATIONAL COMPANY, OF CHICAGO, ILLINOIS, A CORPORATION OF NEW JERSEY

RUNNING LIGHT FOR AIRPLANES

Application filed March 6, 1929. Serial No. 344,642.

My invention relates to improvements in running lights for airplanes and has for one object to provide a new and improved type of running light which can be easily applied to 5 wings and rudder surfaces. Among the objects of my invention are to provide a wing tip light which may be visible both from below and above which will afford some illumination to the ground when the plane is at 10 rest. Other objects will appear from time to time throughout the specification and claims.

My invention is illustrated more or less diagrammatically in the accompanying 15 drawings, wherein—

Figure 1 is a plan view;

Figure 2 is a side elevation of an airplane showing the lights in place;

Figure 3 is a plan view on an enlarged 20 scale of the light itself;

Figure 4 is a side elevation of the light;

Figure 5 is a section along the line 5—5 of 25 Figure 3;

Figure 6 is a section along the line 6—6 of 30 Figure 5;

Figure 7 is a section through the globe;

Figure 8 is a plan view of a holding ring;

Figure 9 is a plan view of the base ring;

Figure 10 is a section through a thin wing 35 section showing my light.

Like parts are indicated by like characters throughout the specification and drawings.

A is an airplane of the conventional type having the usual wings A¹ and rudder A².

35 My light is used by mounting two of them as shown in Figure 1 on opposed sides of the rudder section or by mounting two of them as shown in Figure 2 above and below the wing section or if a very thin wing section is

40 used or if the light is put at a thin part of the section, it may be used by placing one light only at top and cutting away the back of the wing so that light may be seen from below.

45 As indicated in Figures 3 to 6 inclusive, the light comprises a binder plate B which is attached to the underside of the tail surface bounding an aperture B¹ disposed in such surface B². Mounted on this member

50 B is a lamp socket B³ held in place by a

bridge B⁴. This lamp socket is held by means of screws B⁵ to a plate B⁶ integral with the bridge. B⁷ is the electric light bulb attached by means of a bayonet joint as indicated at B⁸ in the electric light socket. B⁹ are the conductors leading out from the socket to any suitable power source.

C is a bowl of glass or other translucent substance reinforced by ribs C¹ and flanged at C² to rest upon the surface of the wing or tail fabric. C³ is a packing ring overlying the flange C² and engaging this packing ring is a locking ring or plate C⁴ having a flat portion C⁵ engaging the wing surface and upwardly flanged at C⁶ to engage the packing ring C³. This member is provided with a series of apertures C⁷ having relatively small notches C⁸ adapted to engage screws C⁹ the heads of which are too big to pass through said notches but small enough to 55 pass through the apertures C⁷. By loosening these screws the plate may be moved from one side so that it may be lifted off when the bowl can be removed or replaced.

The underside of the wing surface is cut 60 away in register with the light when it is desired to use but a single light and in that case since the bottom of the bowl is open the light shines through.

In Figure 10, it will be noted that the solid 65 aircraft wing is apertured but the lower side of the aperture is closed by translucent plate D held in a supporting ring D¹ on the underside of the fabric.

I claim:

1. A running light for airplanes and the like comprising a reinforcing ring adapted to engage one side of the plane fabric, a light source mounted upon said ring, a bowl adapted to engage the opposed side of the 75 fabric, removable means for holding the bowl in direct contact with the fabric in register with the ring.

2. A running light for airplanes and the like comprising a reinforcing ring adapted to engage one side of the plane fabric, a light source mounted upon said ring, a bowl adapted to engage the opposed side of the fabric, removable means for holding the bowl in 80 position against the fabric in register with 100

the ring, the removable means comprising a packing gland associated with the bowl and a flanged ring conforming generally to the contour of the first mentioned ring adapted to engage the packing and clamp the bowl in place.

3. A running light for airplanes and the like comprising a reinforcing ring adapted to engage one side of the plane fabric, a light source mounted upon said ring, a bowl adapted to engage the opposed side of the fabric, removable means for holding the bowl in position against the fabric in register with the ring, the removable means comprising a packing gland associated with the bowl and a flanged ring conforming generally to the contour of the first mentioned ring adapted to engage the packing and clamp the bowl in place, said second ring being apertured to permit passage of holding screws, the apertures having extension slots small enough to hold the screw head and screws passing through both rings to hold the parts together.

25 4. In combination with an airplane wing, a light source arranged adjacent one side of the wing, a removable bowl enclosing the light source on one side, the opposed wing fabric being cut away in register with said bowl to permit light to be seen from the opposed side.

35 5. A running light for airplanes and the like comprising a reinforcing ring adapted to engage one side of the plane fabric, supporting means carried by the ring, a light source mounted on the supporting means, the supporting means and light source being in part in the plane fabric, a bowl adapted to engage the opposed side of the fabric, removable means for holding the bowl in position against the fabric in register with the ring and for clamping the fabric between the ring and bowl, the ring being open in a direction opposed to the bowl.

40 45 Signed at Chicago, county of Cook, and State of Illinois, this 28th day of February, 1929.

EDWARD A. SIPP.
